(57) **CLAIM**

I claim the ornamental design for a jewelry item, as shown and described.

DESCRIPTION

FIG. 1 is a top perspective view of a jewelry item of the new design;

FIG. 2 is a front elevation view thereof, the rear view being a mirror image; and,

FIG. 3 is a top plan view thereof, a bottom plan view, a right side elevation view, and a left side elevation view, all being identical.

The broken line showing of various features of the jewelry item forms no part of the claimed design.
